TABLE LAMP

Charles Clemens, Nashville, Tenn., assignor to Aladdin Industries, Incorporated, Nashville,
Tenn., a corporation of Illinois

Application January 4, 1954, Serial No. 28,327

Term of patent 3½ years

(Cl. D48—20)

To all whom it may concern:

Be it known that I, Charles Clemens, a citizen of the United States, residing at Nashville, county of Davidson, and State of Tennessee, have invented a new, original, and ornamental Design for a Table Lamp, of which the following is a specification, reference being had to the accompanying drawing forming part thereof, in which the figure is a perspective view of a table lamp showing my new design.

The dominant features of my design are shown in solid lines.

I claim:

The ornamental design of a table lamp, as shown and described.
